Attorney.

UNITED STATES PATENT OFFICE.

ALBERT HIRSHHEIMER, OF LA CROSSE, WISCONSIN.

COLTER.

SPECIFICATION forming part of Letters Patent No. 436,478, dated September 16, 1890.

Application filed June 8, 1889. Serial No. 313,624. (No model.)

To all whom it may concern:

Be it known that I, ALBERT HIRSHHEIMER, a citizen of the United States, residing at La Crosse, in the county of La Crosse and State 5 of Wisconsin, have invented certain new and useful Improvements in Colters; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to improvements in 15 colters of the particular class known as "rolling" or "caster" colters; and it consists, first, in the construction and arrangement of the clasp employed for attaching the same to the plow-beam, whereby the colter may be attached to a beam of any form, size, or material 20 without change or addition of parts; second, in the means employed for mounting the fork in which the blade is carried upon the crank, whereby the blade may be secured in 25 any desired position with reference to the beam, either directly underneath the same or at any required distance to one side of and parallel to the same, and still be allowed to vibrate to adjust itself to pass any obstructions 30 in its way, and third, whereby the blade may be rigidly secured in any desired position.

The invention is illustrated in the accompanying drawings, in which—

35 Figure 1 is a side view of the colter; Fig. 2, a section of a plow-beam of the ordinary form of wooden beams, showing the clasp as applied thereto; Fig. 3, a similar view of a beam of the form commonly known as the "T-beam," showing the adaptation of the clasp thereto; Fig. 4, an inside view of the plates forming the clasp; and Fig. 5, an under side view of the colter, showing the method of mounting the fork.

40 The clasp is composed of an upper and lower plate 1 and 2, respectively, the lower plate being provided with a bearing or clasp 3 at one end thereof, in which the colter-crank is mounted and secured by bolts 4. The 45 lower plate has a substantially flat upper bearing-surface 5, adapted to fit closely to

the under side of the beam, and is of some-what greater length than the width of any beam upon which it is to be used. Through its middle and extending longitudinally nearly 55 from end to end is an elongated slot 6 for the reception and adjustment of the bolts used for securing the plates of the clasp in place. The upper plate is of peculiar construction, and, as shown, illustrates the principal feature of this part of the invention. This plate has also either an elongated slot 6 extending nearly from one end to the other, or a slot 60 extending part way from one end to the other, and a bolt-hole in line with the slot and at 65 the other end of the plate. The distance between the bolt-hole and the outer end of the slot, or the length of the slot, is always of sufficient length so that bolts passed through the slot and bolt-hole, or through each end of 70 the slot and through the slot 6 in the under plate may pass outside the beam of the plow.

It will be seen by the construction thus far described that the parts of the clasp may be used upon any beam of wood or metal having 75 substantially parallel or flat upper and lower edges without regard to the thickness of the beam, and the bearing-points upon which the pressure is exerted by the bolts is still close to the lateral edges of the beam, since the 80 bolts 10 may be adjusted in the slots in such a manner as to lie closely against the sides of the beam, and the clasp may be drawn tightly against the upper and lower edges of the beam, the bolts being provided with a 85 lengthened screw-thread to adapt them to different thicknesses of beam. The plates when in position form a clasp absolutely rigid with respect to the beam.

To adapt the clasp for use upon a metal 90 beam of the form commonly known as the "T-beam," or of other forms not having flat or parallel upper and lower sides, the upper clasp-plate is provided upon its under side with a groove or channel 11, adapted to conform with the upper edge of the beam. This channel extends in a direction at right angles to the length of the plate and is intended to fit the top of the beam of inverted-T shape, as shown in Fig. 3. The channel may be of 95 any required form to fit beams of any preferred form, since the groove is not intended 100

necessarily to closely fit the top of the beam, but simply to give a firm bearing for the clasp thereupon to prevent slipping. By reason of the top of the beam entering the groove 5 lateral movement is prevented, and the plate can be as firmly secured as in the case of a flat beam. The clasp is bolted to the beam in the same manner as before described in the case of a flat beam. In case of a beam 10 having flat upper and lower surface, but so narrow that if the clasp was put on in the manner hereinbefore described there might be danger of the clasp tilting to one side, so that the corner of the beam would enter the 15 groove, I prefer to make the plate sufficiently long so that the bolts may both pass through the slot to one side of the groove, leaving the rest of the plate to project to one side of the beam, and thus securing a perfectly flat 20 surface to rest upon the top of the beam. In case of a beam having a flat top and irregular under surface the lower plate instead of the upper might be provided with a groove to conform to the same, or in case of a cylindrical beam both plates may be slightly hollowed out on the inner side to give a firm 25 bearing-surface.

The second principle feature of the invention relates to the means employed for mounting 30 the colter-fork upon crank, whereby the latter may be secured at any desired position with reference to the beam and the colter-blade be still left free to vibrate from one side to the other and at an equal distance in 35 either direction.

The crank-shaft 12 is mounted in a bearing at one end of the clasp in such a manner that it may be turned so that the crank may point either ahead or at any angle to one side or 40 the other, and so that it may be raised or lowered and secured in its bearing at any desired point. This construction is similar to that in common use, and need not be more specifically described. Upon the lower end or shorter 45 arm of the crank 13 is secured the fork 14, between the arms of which the blade 15 is mounted. The head of the fork 14 has a bearing upon the short arm of the crank, the crank extending through an aperture in the head 50 and being secured in place by means of a bolt or screw 16 set within the end of the crank and having a washer 17 thereon, forming a head to hold the fork in place. The length of the bearing formed by the crank is 55 a little greater than the length of the head, so that when the bolt or screw 16 is tightened the cork is still free to turn upon the crank.

To prevent the complete revolution of the fork upon the crank-arm, and to allow the 60 same to vibrate within certain limits, the washer 17 is provided with a radial lug 18 upon one side of its circumference which fits in a notch or aperture 19 in the adjacent part of the head of the fork. The notch is of 65 greater extent than the width of the lug, its width being dependent upon the amount of lateral vibration required, and when the bolt

or screw 16 is tightened the washer is held tightly to the end of the crank; but the fork is left free to vibrate, the lug 18 playing in the notch 19 for that purpose. As the crank is turned either toward or from the land the washer is adjusted so that the lug extends in the direction the blade of the colter is to assume in its center position, and the middle of 70 the notch being in line with the blade of the colter the distance to which the blade is allowed to vibrate is equal in each direction. The usual method has been to adjust the head of the fork upon the crank by means of 75 a screw or key fixed in holes for the purpose formed in the crank and adapted to play in a slot or notch in the head of the fork. The objection to this method is that the screw or key must always be placed in one of a certain 80 number of fixed positions, and as only a few apertures can be made without materially weakening the crank-shaft, in many 85 positions the screw or key will come much nearer to one side than the other of the slot 90 or notch, and hence the amount of vibration allowed upon one side or in one direction is much greater than that in the other.

For the purpose of allowing the fork to be secured in a rigid position with reference to 95 the crank, as may at times be desirable, a notch 20, similar to the notch 19, but just large enough to admit the lug 18, is formed upon the end of the head of the fork. When it is desired to hold the colter rigidly the 100 washer is turned so that the lug enters the notch 20, and the bolt or screw being then tightened, the blade is rigidly secured to the crank.

The washer may be held in place either by 105 a bolt passing through the short arm of the crank and provided with a nut at its upper end, or by means of a set-screw tapped into the lower end of the same, or by means of any other similar device.

The same or a similar device may be employed located upon the top of the head of the fork, the washer in this case being provided with a lug or arm adapted to engage with a slot upon the upper end of the fork-head, a plain washer in that case being used at the lower end of the crank-arm, and both washers may be locked in place by the same bolt.

The lower clamp-plate 2 is preferably 120 formed with one end turned at right angles to its length, as shown at 21, upon the outside of which projection is formed the bearing in which the colter-crank is secured. The object of this projection is chiefly to give a more 125 extended bearing-surface to the crank than would be afforded by the thickness of the plate; but it may also serve a further purpose of allowing the bearing to be either raised or lowered by simply reversing the 130 plate so that the projection shall extend upwardly alongside of the beam, or downwardly below it, in order to have the bearing-point as nearly as possible in line with the

line of resistance as the crank is raised or lowered, and also to increase the limits of such movement.

I claim as my invention—

- 5 1. In a colter, clamp-plates 1 and 2, the said plate 1 having a bolt-hole near one end thereof and a longitudinal slot near the other end, and the plate 2 having a slot whose extremities correspond with said bolt-hole and the outer end of the slot in plate 1, a groove formed across plate 1 on its under side between the bolt-hole and slot, a clamp or bearing for the colter-crank formed upon the extremity of plate 2, and bolts passing through 15 said bolt-hole and slots in said plates, substantially as described, whereby the clamp formed by said plates and bolts may be rigidly attached to a plow-beam of any size or shape.

2. The combination, with the clamp and colter-crank adjustably mounted in bearings thereon, of a colter-fork pivotally secured to the end of said crank by means of a bolt passing therethrough, a removable washer 17, forming an enlarged head at the lower extremity of said bolt, a radial lug upon said washer, the head of said fork having opposite notches formed therein in position to receive said lug, one of said notches being of a width equal to and the other greater than the width of said lug, substantially as and for the purpose herein specified.

In testimony whereof I affix my signature in presence of two witnesses.

ALBERT HIRSHHEIMER.
